UNITED STATES PATENT OFFICE.

AUGUST J. LUNDBERG, OF WEEHAWKEN, NEW JERSEY, ASSIGNOR TO PAC-RITE COMPANY, INC., A CORPORATION OF NEW YORK.

GARMENT-FORM.

1,149,456.

Specification of Letters Patent. Patented Aug. 10, 1915.

Application filed March 22, 1915. Serial No. 16,047.

To all whom it may concern:

Be it known that I, AUGUST J. LUNDBERG, a citizen of the United States, and resident of the town of Weehawken, Hudson county, 5 New Jersey, have invented certain new and useful Improvements in Garment-Forms, of which the following is a specification.

This invention relates to garment forms.

The object of the invention is to provide 10 an improved article of this nature so constructed that it may be made from heavy paper or cardboard and adapted in a simple and very economical structure to provide means serving to retain the shape of the 15 garment when said garment is packed in a box for shipment or serving as a hanger for the support of said garments when desired.

Further objects and advantages of the 20 invention will be set forth in the detailed description which now follows:

In the accompanying drawing: Figure 1 25 illustrates the blank from which the garment form is made. Fig. 2 is a perspective view illustrating the parts of the blank bent, folded and secured to retain the molded form. Fig. 3 is a sectional view through the upper or neck portion of the form.

Like numerals designate corresponding 30 parts in all of the figures of the drawing.

The flat blank shown in Fig. 1 comprises 35 a body portion 5 and a neck portion 6. A transverse strip 7 forming a continuation of the neck portion is creased upon the lines 8, 9 and 10 to provide flaps 11, 12 and 13, the creasing of the material along the lines 8, 9 and 10 rendering it possible to readily 40 bend the flaps to the position illustrated in Fig. 2, where they serve as a support for the upper portion of the form when the latter is placed in a box. When the structure 45 is to serve as a hanger, these flaps are bent together upon each other, as shown in Fig. 3, bringing the openings 14, 15 and 16, into alignment. These flaps at this time reinforce the structure to such an extent 50 that the entire form with the garment thereon may be hung upon a nail, hook or other support without danger of the opening tearing out.

The body portion 5 is provided with inclined slits 17 and 18 and with horizontal slits 19 and 20. Inwardly and upwardly directed slits 21 and 22 separate the lower outer portions of the body from a tail 23 55 provided with a horizontal slit 24. The

slits 21 and 22 separate the lower outer portions of the form from the tail 23, forming the wings 25 and 26 which are provided with tabs 27 and 28. The material of the wings is creased along the lines 29 and 30 60 and in the general direction of the slits 17 and 18. The material of the body is creased at 31 and 32 along the division line between the wings and the tail 23. The provision of these slits and creases forms hinge connections between the wings and body portion and when the lower ends of the wings are brought inwardly these hinges bend along the creases 29—31 and 30—32, allowing the slit 24 to hold the same in position 70 with the center of the form bulged outwardly, as shown in Fig. 2. It will be seen that the entire structure is thus brought to a molded form; in other words it conforms to the general shape of the garment and 75 supports the latter in a box preventing the same being crushed or creased during shipment. The form not only bulges upwardly lengthwise of the structure, but it is also held in bulged formation transversely thereof. This, together with the flaps 11, 12 and 80 13, results in supporting the breast or bust of the garment away from the bottom of the box in which the form is placed, thereby insuring the arrival of the garment at its 85 destination in the best possible condition.

While the particular construction of the 90 form shown and described is well adapted to serve the purpose for which it is intended, it is to be understood that the invention is not limited to the precise construction set forth, but that it includes within its purview whatever is new that comes within the spirit of the appended 95 claims.

Having described my invention, what I claim is:

1. In a device of the character described, a body portion formed of cardboard having a pair of slits within the body portion 100 forming wings upon opposite sides of said body portion, hinge portions extending from the lower end of said slits to the lower edge of the body portion and wings connecting said wings and body portion at opposite 105 edges, said wings and hinge portions being adapted to fold over upon the body portion to produce the required form in the device, and means securing such wings in their folded position.

2. In a device of the character described, a body portion formed of cardboard and provided with a slit, wings connected therewith by hinge portions and adapted to be folded and engaged with said slit to thereby bring the cardboard to bulged formation, and flaps at the upper portion of the device arranged to be bent to support said device in spaced relation to the bottom of the box.
- 10 3. In a device of the character described, a blank made of a single piece of cardboard having a pair of angular slits extending downwardly and inwardly within the body thereof, and a second pair of slits converging upwardly and inwardly from the lower

edge thereof, the said blank having creases therein extending downwardly from opposite ends of the said inwardly extending portions of the first mentioned slits, whereby the side portions of the blank may be 20 folded inwardly upon the central portion of the blank, and means for retaining such side portions in their folded position.

Signed at the city, county and State of New York, this 17th day of March, 1915. 25

AUGUST J. LUNDBERG.
